6575x *De Graaf, Gardner, North Branford Connecticut
Sellers Patent.*

The Schedule referred to in the following patent and making part of the same containing a description in the words of the said D. C. Graaf Gardner have left of his invention in the mode of making wood Buttons, conveniently called dead-eyed Wood Buttons.

So all persons to whom these presents shall come, D. C. Graaf Gardner of North Branford in the County of New Haven and State of Connecticut aforesaid (hereinafter called the Inventor) doth hereby declare that the said D. C. Graaf Gardner have made, invented, constructed, and applied to a new and useful improvement in Wood Buttons commonly called dead-eyed Wood Buttons and such as are now commonly used for suspender, and other purposes, which improvement is specify & describe in the words following viz. This improvement consists in adding to the common Wood Button called the dead-eyed button, such as is now commonly used for suspender, more holes, clearly & also for some other purposes, a row of suitable metal such as tin, brass, copper or other proper metal around the circumference of said Button, and extending toward the middle of said Button far enough on the back side of the Button to have and uniformly set on upon the circumference, say one eighth to one quarter part more or less, of the radius of the Button and extending on the front side of the Button, perhaps twice as far so that the same may make an ornamental form, which dead raised in the middle of the front part of the row, depressed towards the edge of the Button and toward the inner part of the front side of the row, and thus leaving about one half of the front side of the Button uncovered. The holes through which the thread or cord by which the Button is made fast to the garment, are to be those or four more or less in number and inside of the said row of the Button. By this means increased firmness and durability are given to the common wood Buttons aforesaid, while the same is sufficiently ornamental to be used upon such garments as are usually worn in this Country. What I claim

as any improvement and for which only I solicit a patent is the ad-
dition of a metallic rim or edge to the common wood Button now
used for suspender and some other purposes, by means of which the said
Button is rendered firmer and more durable.

In testimony that the above is a true specification of my said in-
vention as above described, I have sealed it in my hand and seal
the 13th day of May 1831.

De Braille Fowler.
